MACHINE FOR SHAPING UPPERS OVER
LASTSBernhardt Jorgensen, Beverly, Mass., assignor
to United Shoe Machinery Corporation, Paterson, N. J., a corporation of New Jersey

Application January 26, 1934, Serial No. 708,435

16 Claims. (Cl. 12—4)

This invention relates to machines for use in the manufacture of shoes for shaping uppers over lasts, and is herein illustrated as applied to a pulling-over machine of a well-known type. 5 many of the characteristic features of which are disclosed generally in Letters Patent No. 1,029,387, granted on June 11, 1912 upon an application of R. F. McFeely. The invention in some aspects has more particular relation to means for laying 10 the marginal portion of the upper inwardly over the shoe bottom and for fastening it at the opposite sides of the forepart of the shoe, and is accordingly herein illustrated as applied to means that operates on the shoe in those locations, al- 15 though it is to be understood that the invention is not thus limited in its applicability. It is also to be understood that in various aspects the invention is not limited to machines of the type disclosed in the above-mentioned Letters Patent.

20 Pulling-over machines of the above-mentioned type include in their organization fastening-inserting mechanisms constructed and arranged to drive at each side of the forepart of the shoe a plurality of fastenings in different locations 25 along the edge of the shoe bottom to fasten the upper in pulled-over position and movable inward laterally of the shoe into positions for driving the fastenings. As constructed for operation on some kinds of shoes, including welt shoes and 30 shoes of the McKay-sewed type, such machines also commonly include overlaying means movable inwardly with the fastening-inserting mechanisms to lay or wipe the marginal portion of the upper over the shoe bottom, the fastening-inserting mechanism and overlaying means at each 35 side of the shoe being so mounted and controlled as to permit it to turn as a unit, in such inward movement, about an axis extending heightwise of the shoe and thereby to assume a position 40 corresponding generally to the lengthwise contour of the side of the shoe to locate the different fastenings at proper distances from the edge of the shoe bottom whatever may be the shape or position of the shoe.

45 An object of the present invention is to provide improvements such as to afford better insurance than heretofore under all conditions that the several fastenings at each side of the shoe will be driven at proper distances from the edge 50 of the shoe bottom and also that the margin of the upper will be laid or wiped inwardly over the shoe bottom in the most satisfactory manner preparatory to the driving of the fastenings. To this and other ends, the invention provides a novel construction and arrangement of fasten-

ing-inserting means and overlaying means such as to render the fastening-inserting means at each side of the shoe more readily and exactly conformable to the shape and position of the shoe and the overlaying means more definitely 5 controllable with respect to its path of movement than in constructions of the character above described. In the construction herein shown the fastening-inserting means for each side of the shoe comprises a pair of fastening-inserting devices so mounted on a supporting member or arm which carries them inwardly over the shoe bottom as to permit relative rectilinear movements of the devices and the arm and of the different devices laterally of the shoe, 10 so that the different devices assume independently of each other positions determined by the shoe, and the arm has also mounted thereon independently of the fastening-inserting devices 15 wipers for wiping the margin of the upper over the shoe bottom by the movement of the arm. The different fastening-inserting devices accordingly adjust themselves to the shoe in a simple and effective manner independently of the wipers, and the latter move in a definite direction 20 unaffected by relative positioning movements 25 of the fastening-inserting devices. As further herein illustrated, inward movement of one of the fastening-inserting devices at each side of the shoe is stopped by direct contact of a member 30 thereon with the side of the shoe while, for a reason hereinafter explained, inward movement of the other device at each side is stopped by contact of a member thereon with upper-clamping means at the side of the shoe which is itself 35 positioned by the shoe. For better insurance that the margin of the upper will, under all conditions, be wiped firmly inward over the shoe bottom, the construction herein shown further comprises 40 means for transmitting inward movements positively to the wipers from their supporting arms, the wipers, however, being yieldable heightwise of the shoe for better conformity to the contour of the shoe bottom.

45 The above and other features of the invention, including various novel details of construction and combinations of parts, will now be more particularly described by reference to the accompanying drawings and pointed out in the claims.

In the drawings,

50 Fig. 1 is a view approximately in front elevation of a portion of a machine in which the invention is embodied, showing the overlaying and fastening-inserting means and other parts that operate at the right-hand side of the shoe as viewed 55

from the front of the machine, with the parts in the positions which they assume at the time of the fastening-inserting operation;

Fig. 2 is a perspective view of a portion of the structure shown in Fig. 1, parts being omitted;

Fig. 3 is a view showing certain parts in section on the line III—III of Fig. 1 and showing, in addition, portions of the upper-pulling grippers and portions of the overlaying and fastening-inserting means that operate at the left-hand side of the shoe and at the end of the toe;

Fig. 4 shows in left-hand side elevation the overlaying and fastening-inserting means shown in Figs. 1 and 3 as operating at the right-hand side of the shoe; and

Fig. 5 is a view from the rear of a portion of the structure shown at the right-hand side of the shoe in Figs. 1 and 3.

In view of the disclosure in the above-mentioned and other prior Letters Patent of the main characteristic features of the general organization of machines of the well-known type illustrated, only such parts as it is necessary to refer to for an understanding of this invention are herein shown and will be particularly described. It will be understood that such a machine is provided with grippers for pulling the upper over the last at the end of the toe and the opposite sides of the forepart, the toe gripper jaws 10 and 12 and the front and rear pairs of side gripper jaws 12 and 14 being shown in section in Fig. 3. The shoe is supported against the pull of the grippers by a sole rest 16. After the pulling of the upper the shoe is engaged at each side of the forepart by a pair of clamp members 18 and 20, the member 18 as shown consisting of a rubber pad which clamps the upper against the side of the last near the edge of the shoe bottom and the member 20 consisting of a metal plate which engages the upper somewhat underneath the forepart to support the shoe against pressure subsequently applied on its bottom face in laying the margin of the upper inwardly over the insole and fastening it. The clamp members 18 and 20 at each side of the shoe are carried by an arm 22 (Figs. 1 and 3) which is swung inwardly toward the shoe about an axis extending heightwise of the shoe as illustrated in the above-mentioned Letters Patent. As also common heretofore, the clamp members 18 and 20 are supported respectively on slides 24 and 26 (Fig. 1) provided with rack teeth engaged by a pinion 28 so that the two members adjust themselves to the shoe in response to pressure of the shoe upon them. The pad 18 is mounted in a block 30 which is swiveled in the slide 24 for movement about an axis extending heightwise of the shoe to permit the pad to adjust itself to the lengthwise contour of the side of the shoe.

After the shoe has been clamped and supported as above described, the margin of the upper is wiped inwardly over the insole at the end of the toe and the sides of the forepart by overlaying or wiping means, and fastenings, customarily tacks, are driven by fastening-inserting devices through the upper and the insole near the edge of the shoe bottom to fasten the upper in pulled-over position. The overlaying and fastening-inserting mechanisms are moved inwardly toward the shoe as hereinafter described to effect the overlaying operation and to bring the fastening-inserting devices into proper positions for the insertion of the fastenings, and in such inward movements of these mechanisms they act on members 32 on the grippers, one of which members is shown in Fig. 1,

to cause the gripper jaws to release the margin of the upper. The overlaying and fastening-inserting mechanism for operating on the upper at the end of the toe comprises a wiper 34 and a fastening-inserting device 36 (Fig. 3) which need not be described in detail. The mechanisms for thus operating on the upper at the opposite sides of the forepart are supported on opposite side arms 38 which are mounted for inward and outward swinging movements laterally of the shoe as fully disclosed in the above-mentioned Letters Patent. Fastened to the lower end portion of each arm 38 and extending partially beneath the lower end of the arm is a bracket 40 to the lower end of which is fastened by a screw-threaded spindle 42 and a nut 44 a wiper-supporting block 46. In this block 46 are recesses in which are positioned wipers 48 and 50, these wipers comprising plates extending lengthwise in directions laterally of the shoe and having upturned inner ends to permit them to ride easily over the edge of the shoe bottom. The wipers are mounted in the recesses in the block 46 for rocking movements heightwise of the shoe about a pin 52 (Fig. 1) which is mounted in the bracket 40 and against which the wipers bear substantially midway of their lengths. Spring-pressed plungers 54, one for each of the wipers 48 and 50, are mounted in the block 46 and by pressing upwardly against the outer end portions of the wipers tend to rock their inner end portions downwardly, the plungers being yieldable to permit rocking of the wipers in the opposite direction by action of the shoe thereon. As thus far described the wipers and their controlling means are generally similar to what has been commonly used heretofore in many machines of the illustrated type. In the construction herein shown, however, the wipers are not yieldable lengthwise, i. e., in directions laterally of the shoe relatively to the arm 38 as heretofore, but are held positively against such yield by nuts 56 threaded on stems 58 which project outwardly from the block 46 and engaging downturned ends 60 of the wipers, these ends having slots 61 therein to permit the rocking of the wipers heightwise of the shoe as above described. Furthermore, since the block 46 is fastened rigidly to the bracket 40 which is, in turn, fastened rigidly to the arm 38, the wipers are not permitted to swing or turn about an axis extending heightwise of the shoe in the wiping operation as common heretofore.

In the construction herein shown each of the arms 38 carries two upper-fastening devices or tackers comprising plates 62 and 64 mounted respectively at opposite sides of the arm and of the bracket 40 on the arm. The plate 62, which is located at the side of the arm nearer the toe end of the shoe, has mounted thereon a tack holder 66 (Fig. 4) comprising spring-pressed tack fingers of well-known form provided with tack pockets to receive two tacks to be driven in locations at or near the tip line of the upper, if the upper is provided with a toe tip, and associated with these tack pockets are a pair of drivers 68 for driving the tacks. The plate 64, which is at the side of the arm 38 farther from the toe end of the shoe, carries a tack holder 70 (Fig. 4) having a tack pocket to receive a single tack, and associated with this tack pocket is a single driver 72. The two plates 62 and 64 are so mounted as to be capable of rectilinear movements relatively to each other and relatively to the arm 38 in directions widthwise of the shoe. For this purpose the plate 62 has therein slots 75

74 and 76 through which project from the bracket 40 studs 78 and 80 to support the plate. Fastened to the plate 62 by a screw 82 threaded in the plate is a thin plate 84 having lower edge 5 portions which enter slots in the studs 78 and 80 to hold the plate 62 in position on the arm 38 and the bracket 40. The screw 82 has a winged head 86 thereon for turning it, this head being spaced from the plate 84 by a collar 88 and through the 10 collar clamping the plate 84 to the plate 62. A slot 90 in the plate 84 permits the latter to be lifted when the screw 82 is loosened, in case it is desired to remove the plate 62 by slipping it off the studs 78 and 80. The plate 64 is similarly 15 mounted on studs 92 and 94 projecting from the rear side of the bracket 40 through slots in the plate, and is held on the studs by a thin plate 96 projecting into grooves in the studs, this plate being fastened to the plate 64 by a screw 98 20 similar to the screw 82 and having a winged head 99 thereon. The two plates 62 and 64 are engaged on their outer ends by bell-crank levers 100 pivotally mounted on the bracket 40 and controlled by springs 102 which, through these 25 levers, tend to move the plates inwardly toward the shoe relatively to the arm 38 and position them initially at limits of inward movement determined by the studs 78, 80 and 92, 94 in engagement with the plates at the outer ends of 30 the slots in the plates.

For limiting the inward movement over the bottom of the shoe of that fastening-inserting device which is mounted on each arm 38 nearer the end of the toe and for thus determining the 35 position of that device relatively to the shoe in the fastening-inserting operation, there is fastened to each plate 62 a bracket 104 in which is threaded a screw 106 having a rounded inner end 108 arranged to engage the side of the shoe forwardly of the clamping pad 18, the screw being adjustable in the bracket to vary the distance from the edge of the shoe bottom at which the two fastenings are driven from the plate 62. To assist in holding the screw in adjusted position 40 there is provided a spring-pressed ball 109 which is mounted in the bracket 104 and is arranged to enter one or another of a number of depressions formed in the sides of the screw. For similarly limiting the inward movement of 45 the rearmost fastening-inserting device on each arm 38 there is provided on this device means that acts, not by direct contact with the side of the shoe, but by contact with a face 110 on the side clamp block 30 (Fig. 2) previously referred 50 to as swiveled in the slide 24. This means comprises an arm 112 (Figs. 2 and 4) arranged to contact with the face 110 and mounted fast on a threaded spindle 114 which extends lengthwise through spaced lugs 116 (Fig. 5) formed on 55 a bracket 118 fast on the plate 64. Threaded on the spindle 114 between the lugs 116 is a knurled wheel 120 which may be turned to adjust the arm 112 in directions widthwise of the shoe and thus to vary the distance from the 60 edge of the shoe bottom at which the fastening is driven from the plate 64. A spring-pressed ball 122 mounted in one of the lugs 116 is arranged to enter depressions in the side of the wheel 120 to assist in holding the arm 112 in 65 adjusted position. To prevent the arm 112 from turning when the wheel 120 is turned, a lug 124 (Fig. 4) projects from the arm into a slot in the bracket 118, this slot extending in directions parallel to the directions of adjustment of the 70 arm. Since the block 30 adjusts itself to a po-

sition determined by the lengthwise contour of the side of each shoe as hereinbefore explained, the face 110 on the block, which is engaged by the arm 112 in a location substantially under the tack holder 70 on the plate 64, serves to determine in a satisfactorily accurate manner the location of the rearmost side tack relatively to the edge of the shoe bottom. Such means for controlling the plate 64 is preferable to means on the plate arranged to contact directly with the side of the shoe rearwardly of the clamping pad 18, since in some cases the side face of the shoe in that location, especially the inner side face, may slope rather abruptly inward toward the shank portion of the shoe. 15

From the foregoing description it will be seen that when the arms 38 are swung inwardly the tacker plates 62 and 64 on each arm are stopped respectively by contact of the screw 106 with the side of the shoe and contact of the arm 112 with the side clamp block 30 which is itself positioned by the shoe, after which the arm continues its inward movement relatively to the plates against the resistance of the springs 102 which control the plates. The inward movement of the arm 20 itself is limited in a substantially positive manner by the above-mentioned block 30, the face 110 of which is engaged by a stop 126 (Fig. 2) secured adjustably to the block 46 on the lower end of the arm by a nut 127 threaded on the previous 25 mentioned spindle 42. 30

The previously mentioned tack drivers 68 and 72 at each side of the machine are operated by a driver bar 128 on the arm 38, this driver bar being impelled downwardly by spring means (not shown) as heretofore in machines of the illustrated type. In the construction herein shown the connections between the bar 128 and the drivers are such as to permit relative rectilinear movements of the arm 38 and the plates 62 and 64 laterally of the shoe as hereinbefore described while maintaining at all times an operative relation between the bar and the drivers. The drivers 68 are fast in a block 130 (Figs. 1 and 4) movable downwardly and upwardly along guideways 35 132 in the plate 62, and the driver 72 is fast in a block 134 similarly movable downwardly and upwardly along guideways in the plate 64. Laterally offset portions of the blocks 130 and 134 lie 40 respectively in guideways 136 and 138 (Fig. 4) 45 formed in opposite sides of the lower end portion of the driver bar 128 and extending in directions parallel to the directions of relative movement of the arm 38 and the plates 62 and 64. Operative connections are thus maintained at all times 50 between the bar 128 and the blocks 130 and 134 55 irrespective of the positions of the plates 62 and 64 relatively to each other and to the arm 38. 60

Tacks are supplied to the tack pockets in the tack holders 66 and 70 at each side of the machine through ducts 140 in the plates 62 and 64 from other ducts 142 formed in a stationary bracket 144 and arranged to register with the ducts 140 when the arm 38 is in its outer starting position. Tubes 146 leading from the usual 65 source of tack supply are supported at their lower ends in the bracket 144. This bracket is fast on another bracket 148 secured to a portion 150 of the frame of the machine. The ducts 140 are continuous as far downwardly as the driver passages above the tack pockets, and their upper ends are in close relation to the lower ends of the ducts 142 when the arm 38 is in its outer position. This construction affords satisfactory insurance that the tacks will be fed properly to 70 75

the tack pockets in case very small tacks are used, as is herein illustrated and as is frequently the practice in operating, for example, on shoes of the McKay-sewed type.

- 5 The operation of the construction provided by this invention will be clearly understood from the foregoing description. It will be seen that the different fastening-inserting devices at each side of the shoe, which are relatively movable laterally of the shoe in a simple and direct manner as described when the arms 38 receive their inward movements, adjust themselves readily and effectively to the portions of the shoe where the respective fastenings are to be driven; and also 10 15 that the wipers are moved inwardly over the shoe bottom in definitely determined paths unaffected by the relative positioning movements of the fastening-inserting devices.

While the novel means provided by this invention is herein illustrated as operating upon a shoe having an insole of the type used, for example, in McKay-sewed work, it is to be understood that the invention is by no means limited to the manufacture of shoes of that type.

20 25 Having described the invention, what I claim as new and desire to secure by Letters Patent of the United States is:

- 25 30 35 40 45 50 1. In an upper-shaping machine, the combination with means for shaping the upper of a shoe over a last, of devices for inserting fastenings at the opposite sides of the shoe bottom to fasten the upper, members supporting said devices and movable inward laterally of the shoe to carry the devices into fastening-inserting positions, the devices being so mounted on said members as to permit relative movements of the devices and members laterally of the shoe, overlaying means also carried by said supporting members for laying the marginal portion of the upper inwardly over the shoe bottom, positive means for transmitting inward movements from said members to the overlaying means, means controlled by the shoe for stopping the inward movements of said fastening-inserting devices when the devices are in proper relation to the shoe, and spring means controlling said fastening-inserting devices and yieldable to permit further inward movements of said members and the overlaying means thereon after said devices have come to a stop.

55 60 65 70 75 2. In an upper-shaping machine, the combination with means for shaping the upper of a shoe over a last, of a plurality of fastening-inserting devices for each of the opposite sides of the shoe arranged respectively to insert fastenings in different locations along the edge of the shoe bottom to fasten the upper, opposite members each supporting the fastening-inserting devices at one side of the shoe and movable inward laterally of the shoe to carry the devices into fastening-inserting positions, the devices on each of said members being provided with means for stopping them each independently in a position determined by the shoe and being yieldable relatively to the supporting member to permit the latter to continue its inward movement, overlaying means also carried by said supporting members for laying the marginal portion of the upper inwardly over the shoe bottom, and means for transmitting inward movements unyieldingly from said members to the overlaying means.

3. In an upper-shaping machine, the combination with means for shaping the upper of a shoe over a last, of a plurality of fastening-inserting devices for each of the opposite sides of the shoe

arranged respectively to insert fastenings in different locations along the edge of the shoe bottom to fasten the upper, opposite side arms each supporting the fastening-inserting devices at one side of the shoe and movable inward laterally of the shoe to carry the devices into fastening-inserting positions, the devices being so mounted on said arms as to permit relative movements of the devices and arms laterally of the shoe and also relative movements laterally of the shoe of the different devices on each arm, wipers also of the devices and arms laterally of the shoe and carried by said arms for wiping the marginal portion of the upper inwardly over the shoe bottom, positive means for transmitting inward movements from said arms to the wipers, means controlled by the shoe for stopping the inward movement of each of said fastening-inserting devices independently of the others, and spring means controlling said fastening-inserting devices and yieldable to permit further inward movements of said arms and the wipers thereon after said devices have come to a stop.

4. In an upper-shaping machine, the combination with means for shaping the upper of a shoe over a last, of devices for inserting fastenings at the opposite sides of the shoe bottom to fasten the upper, members supporting said devices and movable inward laterally of the shoe to carry the devices into fastening-inserting positions, the devices being so mounted on said members as to permit relative rectilinear movements of the devices and members laterally of the shoe, overlaying means supported on said members independently of said fastening-inserting devices for laying the marginal portion of the upper inwardly over the shoe bottom, means controlled by the shoe for stopping the inward movements of said fastening-inserting devices when the devices are in proper relation to the shoe, and spring means controlling said devices and yieldable to permit further inward movements of said supporting members after said devices have come to a stop.

5. In an upper-shaping machine, the combination with means for shaping the upper of a shoe over a last, of a plurality of fastening-inserting devices for each of the opposite sides of the shoe arranged respectively to insert fastenings in different locations along the edge of the shoe bottom to fasten the upper, opposite members each supporting the fastening-inserting devices at one side of the shoe and movable inward laterally of the shoe to carry the devices into fastening-inserting positions, the devices on each member being so mounted as to permit relative rectilinear movements of the devices and the member laterally of the shoe and each device having means thereon for stopping it in a position determined by the shoe, spring means controlling said devices and yieldable to permit the supporting members to continue their inward movements after the devices have come to a stop, and overlaying means supported on said members independently of the fastening-inserting devices for laying the marginal portion of the upper inwardly over the shoe bottom by the movements of the members.

6. In an upper-shaping machine, the combination with means for shaping the upper of a shoe over a last, of a plurality of fastening-inserting devices for each of the opposite sides of the shoe arranged respectively to insert fastenings in different locations along the edge of the shoe bottom to fasten the upper, opposite side arms each supporting the fastening-inserting de-

- 5 vices at one side of the shoe and movable inward laterally of the shoe to carry said devices into fastening-inserting positions, the devices on each arm being so mounted as to permit relative rectilinear movements of the devices and the arm laterally of the shoe, wipers supported by said arms independently of said fastening-inserting devices for wiping the marginal portion of the upper inwardly over the shoe bottom, means controlled by the shoe for stopping the inward movement of each of said fastening-inserting devices independently of the others, and spring means controlling said devices and yieldable to permit further inward movements of said arms after 10 said devices have come to a stop.
7. In an upper-shaping machine, the combination with means for shaping the upper of a shoe over a last, of a plurality of fastening-inserting devices for each of the opposite sides of the shoe arranged respectively to insert fastenings in different locations along the edge of the shoe bottom to fasten the upper, opposite side arms each supporting the fastening-inserting devices at one side of the shoe and movable inward laterally of the shoe to carry said devices into fastening-inserting positions, the devices on each arm being so mounted as to permit relative bodily movements of the devices and the arm laterally of the shoe and each device having means thereon for stopping it independently in a position determined by the shoe, spring means controlling said devices and yieldable to permit continued movements of said arms after the devices have come to a stop, wipers supported by said arms independently of the fastening-inserting devices for wiping the marginal portion of the upper inwardly over the shoe bottom, said wipers being yieldable heightwise of the shoe relatively to the arms, and means for transmitting inward movements unyieldingly from said arms to the wipers.
8. In an upper-shaping machine, the combination with means for shaping the upper of a shoe over a last, of a plurality of fastening-inserting devices for each of the opposite sides of the shoe arranged respectively to insert fastenings in different locations along the edge of the shoe bottom to fasten the upper, opposite side arms each supporting the fastening-inserting devices at one side of the shoe and movable inward laterally of the shoe to carry said devices into fastening-inserting positions, each of said devices comprising a plate having a tack holder and a driver supported thereon, each plate being so mounted on its supporting arm as to permit relative rectilinear movement of the plate and the arm laterally of the shoe, wipers supported on said arms independently of said plates for wiping the marginal portion of the upper inwardly over the shoe bottom, means on the different plates for stopping their inward movements in positions determined by the shoe, and spring means tending to impart to said plates inward movements relatively to the arms and yieldable to permit further inward movements of the arms after the plates have come to a stop.
9. In an upper-shaping machine, the combination with means for pulling the upper of a shoe over a last at the opposite sides of the last, of means for clamping the upper against the opposite sides of the last after the upper has been pulled, a plurality of fastening-inserting devices for each of the opposite sides of the shoe arranged respectively to insert fastenings in different locations along the edge of the shoe bottom to fasten the upper, and means for carrying said devices inward laterally of the shoe into fastening-inserting positions, the devices at each side of the shoe being so mounted and controlled as to permit them to yield independently of each other in response to resistance to their inward movements and being arranged respectively to contact with the side of the shoe and with said clamping means to limit their inward movements.
10. In an upper-shaping machine, the combination with means for pulling the upper of a shoe over a last at the opposite sides of the last, of means for clamping the upper against the opposite sides of the last after the upper has been pulled, a plurality of fastening-inserting devices for each of the opposite sides of the shoe arranged respectively to insert fastenings in different locations along the edge of the shoe bottom to fasten the upper, means for carrying said devices inward laterally of the shoe into fastening-inserting positions, the devices at each side of the shoe being so mounted and controlled as to permit them to yield independently of each other in response to resistance to their inward movements, one of said devices at each side of the shoe having a member for engaging the shoe to limit its inward movement, and another of said devices at each side of the shoe having a member for limiting its inward movement by engagement with the upper-clamping means, each of said members being adjustable to vary the relation of the corresponding device to the shoe.
11. In an upper-shaping machine, the combination with means for pulling the upper of a shoe over a last at the opposite sides of the forepart, of means for clamping the upper against the opposite sides of the forepart of the last after the upper has been pulled, a plurality of fastening-inserting devices for each of the opposite sides of the shoe arranged respectively to insert fastenings in different locations along the edge of the shoe bottom to fasten the upper, opposite side arms each supporting the fastening-inserting devices at one side of the shoe and movable inward laterally of the shoe to carry said devices into fastening-inserting positions, the devices on each arm being so mounted as to permit relative movements of the devices and the arm laterally of the shoe and also to permit relative movements of the different devices laterally of the shoe, and spring means tending to impart to the devices on each arm inward movements relatively to the arm and yieldable to permit further inward movement of the arm after the devices have come to a stop, that fastening-inserting device which is nearest the toe end of the shoe on each arm having means for stopping its inward movement by contact with the shoe, and that device which is farthest from the toe end of the shoe on each arm having means for stopping its inward movement by contact with said upper-clamping means.
12. In an upper-shaping machine, the combination with means for pulling the upper of a shoe over a last at the opposite sides of the forepart, of means for clamping the upper against the opposite sides of the forepart of the last after the upper has been pulled, a plurality of fastening-inserting devices for each of the opposite sides of the shoe arranged respectively to insert fastenings in different locations along the edge of the shoe bottom to fasten the upper, opposite side arms each supporting the fastening-inserting devices at one side of the shoe and movable inward laterally of the shoe to carry said devices into fastening-inserting positions, the devices on each arm being so mounted as to permit

relative movements of the devices and the arm laterally of the shoe and also to permit relative movements of the different devices laterally of the shoe, spring means tending to impart to the devices on each arm inward movements relatively to the arm and yieldable to permit further inward movement of the arm after the devices have come to a stop, one of the fastening-inserting devices on each arm having means for limiting its inward movement by contact with the shoe, another of the fastening-inserting devices on each arm having means for limiting its inward movement by contact with said upper-clamping means, and means for limiting inward movement of each arm by contact with said upper-clamping means.

13. In an upper-shaping machine, the combination with means for shaping the upper of a shoe over a last, of a plurality of fastening-inserting devices arranged respectively to insert fastenings in different locations along the edge of the shoe bottom to fasten the upper, a member supporting said devices and movable inwardly to carry the devices into fastening-inserting positions, the devices being so mounted on said member as to permit relative rectilinear movements of said devices and member and thus to permit the devices to come to a stop while the member continues its inward movement, each of said devices having means thereon for stopping it independently in a position determined by the shoe, and overlaying means supported by said member independently of said devices for laying the marginal portion of the upper inwardly over the shoe bottom by the movement of the member.

14. In an upper-shaping machine, the combination with means for shaping the upper of a shoe over a last, of a plurality of fastening-inserting devices arranged respectively to insert fastenings in different locations along the edge of the shoe bottom to fasten the upper, a member supporting said devices and movable inwardly to carry the devices into fastening-inserting positions, the devices being so mounted on said member as to permit relative bodily movements of said devices and member and thus to permit the devices to come to a stop while the member continues its inward movement, each of said devices having means thereon for stopping it independently in a position determined by the shoe,

overlaying means supported by said member independently of said devices for laying the marginal portion of the upper inwardly over the shoe bottom by the movement of the member, positive means for transmitting inward movement from said member to the overlaying means, and yieldable means for transmitting inward movement from said member to said fastening-inserting devices.

15. In an upper-shaping machine, the combination with means for shaping the upper of a shoe over a last, of a plurality of fastening-inserting devices arranged respectively to insert fastenings in different locations along the edge of the shoe bottom to fasten the upper, a member supporting said devices and movable inwardly to carry the devices into fastening-inserting positions, the devices being so mounted on said member as to permit relative movements of said devices and member and thus to permit the devices to come to a stop while the member continues its inward movement, each of said devices having means thereon for stopping it independently in a position determined by the shoe, and spring-controlled levers tending to move said devices inward relatively to said member and yieldable to permit continued movement of the member after the devices have come to a stop.

16. In an upper-shaping machine, the combination with means for shaping the upper of a shoe over a last, of a plurality of fastening-inserting devices arranged respectively to insert fastenings in different locations along the edge of the shoe bottom to fasten the upper, a member supporting said devices and movable inwardly to carry the devices into fastening-inserting positions, the devices being so mounted on said member as to permit relative rectilinear movements of said devices and member and thus to permit the devices to come to a stop while the member continues its inward movement, means for stopping said devices in positions determined by the shoe, each of said devices including a driver and a block carrying the driver and movable to operate it, a driver bar on said member for operating the drivers through said blocks, and sliding connections between said blocks and the driver bar including guideways extending in directions parallel to the directions of relative movement of said devices and member.

BERNHARDT JORGENSEN.

CERTIFICATE OF CORRECTION.

Patent No. 1,990,492.

February 12, 1935.

BERNHARDT JORGENSEN.

It is hereby certified that error appears in the printed specification of the above numbered patent requiring correction as follows: Page 4, second column, line 12, claim 3, strike out the words "of the devices and arms laterally of the shoe and"; and that the said Letters Patent should be read with this correction therein that the same may conform to the record of the case in the Patent Office.

Signed and sealed this 6th day of August, A. D. 1935.

(Seal)

**Leslie Frazer
Acting Commissioner of Patents.**
